BLAST FURNACE STOVE

Selwyne P. Kinney, Crafton, and Louis M. Hartwick, Beaver, Pa., assignors, by mesne assignments, to S. P. Kinney Engineers, Inc., Pittsburgh, Pa., a corporation of Pennsylvania

Application January 15, 1945, Serial No. 572,812

7 Claims. (Cl. 263—15)

1

This invention relates to blast furnace stoves, and more particularly to a bottom structure for such stoves.

The conventional blast furnace stove comprises a cylindrical shell usually of metal lined with refractory having a dome shaped top, and which may have a vertical height of 80 feet or more. On the interior of the stove is a vertical flue, usually eccentrically located and referred to as a combustion chamber. Gas and air are introduced through a burner at the bottom of the flue, and the burning gases of combustion travel up the flue to the top. The remainder of the interior of the stove is filled with checker brick and the hot combustion gases travel downwardly through this checker work, heating the checker brick. When the interior of the stove has become sufficiently hot, combustion is stopped, and air is blown in reverse direction through the stove, and the air which is thus heated is used in operating the blast furnace.

The checker brick is supported on a stove bottom which is elevated above the actual bottom of the stove. This bottom comprises vertical supporting columns of structural metal which support horizontally extending girders. These girders in turn support a metal grid structure on which the superimposed column of checker brick is carried. This elevated stove bottom is necessary to provide an air chamber under the column of checker brick. A stack connection leads from this chamber, and when the stove is operating on the air heating or blast cycle the air to be heated is introduced through the stack pipe into this chamber.

When the stove is operating on the heating cycle, the hot gases of combustion passing down through the checker brick and entering the chamber below the bottom are still at a very high temperature, and temperatures are encountered at the bottom of the stove which are above the critical temperature of the structural steel, thus weakening the steel and rendering its performance unpredictable. The weight of the superimposed column of checker brick is very substantial, and if any part of the bottom fails, the checker brick shifts and the stove is impaired, if not rendered useless. One of the most serious difficulties in the operation of blast furnace stoves is due to bottom failure. Whereas, their expected life is twenty years, they will sometimes fail in a comparatively few months or years. Not only is the cost of these structures very substantial, ranging upwardly from eighty thousand (\$80,000.00) dollars, but operations of

2

the blast furnace may be impaired when the stove has to be taken out of service for repairs.

Heretofore the only way to guard against failure of the stove bottom has been to use sections of extra heavy metal, many times heavier than that theoretically required to safely carry the load.

According to the present invention protection is provided against failure of the bottom by fluid cooling, as for example by the provision of ducts along or constituting a part of the structure. Hence, they may be kept, during the operation of the furnace, even for very long periods of time on a heating cycle, at a temperature such as to avoid danger to the bottom. The invention further contemplates the provision of a protective arrangement in the stove so that where water is used as the cooling medium accumulations of water in the bottom of the stove may be avoided. The invention further contemplates an arrangement whereby the functioning of the cooling system may be properly checked and supervised and warning given of the failure in any part of the system.

25 The invention may be more fully understood by reference to the accompanying drawings, in which:

Figure 1 is a vertical section, more or less conventional, through a blast furnace stove of the type to which the present invention pertains;

Figure 2 is a detail view partly in section and partly in elevation showing on a larger scale a portion of the stove bottom;

Figure 2a' is a section taken on line II—II of Figure 2;

Figure 3 is a view partly in section and partly in elevation at right angles to Figure 2;

Figure 4 is a more or less schematic section in the plane of line IV—IV of Figure 1, showing the connections for water cooling the columns;

Figure 5 is a more or less schematic view showing a top plan view of the girders with provision for cooling them;

Figure 6 is a top plan view, also of a conventional character, showing a plurality of the grid units with their water cooling circuits;

Figure 7 is a fragmentary view showing a portion of the stove bottom with means for warning against the accumulation of the water in the stove bottom, and for draining the water therefrom;

Figure 8 is a detail view showing a portion of the discharge line of any one of the water cooling circuits to give a visible indication of the failure of the cooling circuit or overheating;

Figure 9 is a circuit diagram showing an electric protective system for warning against the overheating of any individual part of the assembly;

Figure 10 is a longitudinal vertical section of a modified form of column;

Figure 11 is a transverse section in the plane of line XI—XI of Figure 10; and

Figure 12 is a fragmentary view similar to Figure 3 showing a modified cooling arrangement.

Referring first to Figure 1, the cylindrical shell of the stove is designated 2, and it is of conventional construction with a vertical flue on the interior thereof constituting the combustion chamber 3, this combustion chamber being eccentrically positioned and having a burner 4 at its lower end. The dome-shaped top of the stove is open, but extending from the level of the flue downwardly is a checker brick construction 5 supported on a bottom designated generally as 6. The bottom 6 is conventionally made up of a number of grid sections 7, these grid sections having closely spaced horizontal bars connected together, the grids covering substantially the entire interior of the stove in the space beneath the checker brick. These grids are laid in end-to-end and side-by-side relation and are supported on horizontal girders 8. The horizontal girders in turn are carried on vertical supports 9 which rest on the bottom foundation of the stove, the bottom foundation being designated generally as 10. It is usually covered with refractory bricks. There is a stack pipe 4a leading from the chamber under the grids 7. A hot blast off-take pipe is indicated at 4b.

So much of the structure as has heretofore been described is conventional. According to the present invention the grids 7, girders 8, and columns 9 are formed of metal and are water cooled.

The construction of these elements according to the present invention is best shown in Figures 2, 2a and 3. Each column 9 is a rolled structural H section. At the bottom of the section is a base plate 11 and at the top of the column is a cap plate 12. Welded to the flanges of the H sections are plates 13, these plates also being welded at their tops and bottoms to the cap and base plates 12 and 11 respectively. Thus there is provided two closed ducts 14 and 15, one on each side of the web of the column. Adjacent its lower end the web is perforated as indicated at 16 to permit the flow of water or other cooling fluid from one passage to the other. A water intake pipe is welded into the plate 13 on one side of the column and a water outlet pipe is welded into the column at the other side of the column, these inlet and outlet pipes being designated 17 and 18 respectively. With this arrangement, water or other cooling fluid can be introduced into the duct 14 to flow lengthwise down the column through the openings 16 and up the duct 15 to the outlet pipe 18.

The cap plate 12 at the top of the column has upstanding flanges 12a thereon, and the girders 8 which extend horizontally rest on the cap plates 12 and are confined against lateral movement by the flanges 12a. The girders may also be formed rolled metal H sections, and plates 8a and 8b are welded to the flanges thereof to form two horizontally extending ducts 19 and 19a respectively. The ends of these ducts are closed by plates 8c welded across the ends of the girders. A water inlet pipe 20 is welded into one of the plates 8a and a water outlet pipe 21 is welded into the plate 8b. The web of the section is perforated as

indicated at 22 at that end of the section which is remote from the inlet and outlet pipes so that the water travels lengthwise at one side of the girder, through the holes 22, and lengthwise along the other side of the girder through the duct 20 thereof through the outlet pipe 21.

Customarily the bars constituting the grids 7 are solid bars, but according to the present invention these bars are comprised of similar shaped sections 7a set edgewise with a plate 7b welded to the flanges thereof to form a longitudinally extending duct 7c. At each end of the channel the duct is closed by a plate 7d which is welded thereto. A number of parallel bars or channels formed in this manner constitute a unit, and all of the bars of the unit may be connected by water pipes 23, which are alternately located at opposite ends of the bars, as best shown in Figure 6. There is a water inlet connection 24 at the end of one of the outside bars of the section, and an outlet pipe 25 at the end of the other outside bar of the section. Between the inlet and the outlet, the water or other cooling fluid may travel horizontally through one bar, through the pipe 23, along the next bar, and through the pipe 23 to the third bar, etc., flowing in this back and forth direction in the alternate bars until the outlet 25 is reached.

From the foregoing, it will be seen that the cooling girders and grids may all be cooled by the circulation of cooling fluid, preferably water, therethrough. In Figure 4 there is shown schematically a water-circulating arrangement which may conveniently be used so that all of the columns are connected in parallel with a common water inlet connection, and are also connected in parallel with a common water outlet connection. In this figure, the main water inlet pipe is designated 26. It has branches 26a that lead to the intake pipe 17 of the several columns. The water outlet main is designated 27 and it has branches 28 that connect to the outlet connections 18. Preferably there are no unions or pipe connections in the system, it being preferred to join all communicating pipes by welding. While it is of course possible to connect one or more of the columns in series so that the water will flow from one into the next, it is preferred that they all be connected in parallel as this makes detection of any failure easier to locate.

Likewise, all of the inlet pipes 20 for the girders are connected through pipe 29 to a main water supply main 30, and the outlet pipes 21a are connected to an outlet manifold or main 31. In the same manner, there is a single source of water supply 32 connected through connections 24 with the several grid units, as shown in Figure 6, and the top pipes 25 of all of the grid units are connected through pipes 35 with an outlet main 36.

The water circulating systems for the columns, girders and grids, are preferably all connected in parallel, although here again it might be possible to connect them in series, but being connected in parallel, location of a failure may be detected more quickly.

Each outlet main preferably terminates in some kind of a visible flow indicator of the type illustrated in Figure 8 in which A designates the terminal of one of the outlet mains and B designates a spaced funnel-shaped collector into which A discharges. As long as there is a visible flow of water from A into B, the stove tender will know that the water is flowing through the system to which such discharge indicator is connected, in a proper manner. If the water does

not flow, or if only steam is flowing, the tender or operator may see it immediately. Since there is one of these sight flow devices for the column system, another for the girder system, and a third for the grid system, the operators may know immediately if any one of the systems is not properly working.

In order to give a more accurate indication of just where there is a failure of the water circulation, electrical indicating devices employing thermostats or thermocouples may also be used. This is illustrated in Figure 9.

In Figure 9, there is shown one post or column unit, one girder unit and a grid unit. Each has a thermostat or thermocouple, i. e., a heat responsive circuit closer, applied thereto, as indicated schematically at 37, 38 and 39 respectively. Each is in circuit, through a separate indicator 37a, 38a and 39a, respectively, which may be signal lamps, with a source of current 34. There may be any desired number of such indicating means in the cooled supporting system, although it is not normally deemed necessary to have an indicator on every unit. An increase in temperature is by such means, indicated by a light or other indicator and the region of such increase noted.

Unbeknown to the operator, a leak might occur in the system resulting in an undesirable accumulation of water in the bottom of the stove. To guard against this, the floor 10 of the chamber may be sloped toward a sump 40 in which is a float 41 and from which leads a drain 42 with a valve 43, outside the stove, therein. If there is a leak, water will flow into the sump, and raise the float. The float operates a circuit closer 44 to an alarm or signal 45, which notifies the tender of the leak. The tender may then open the valve 43, or such operation could be effected automatically by the float controlled electric circuit.

Instead of using rolled structural columns as described, heavy tubular columns may be used, as shown in Figures 10 and 11, wherein the outer tube 50 is the main column with a base 51 and a cap 52. It is of heavy metal. Inside the tubular column is a smaller tubular column 53, preferably co-extensive in height with 50 so as to aid in carrying the load. There is a water inlet nipple 54 leading to the bottom of tube 53 and openings 55 allow the water to flow into column 50 to outlet 56 at the base thereof.

In the foregoing description we have indicated that water is used as the cooling medium, but it will be understood that any other suitable fluid may be circulated through the ducts in lieu of water, and the term "water" is used to include equivalent cooling of fluids, including air or other liquids or gases.

In the foregoing description we have also described the circulating system as being a closed system, this being the most desirable. However, it is not necessary that the system be enclosed, as it is within the contemplation of our invention that when the stove is on the heating cycle, cooling fluid may be injected into the lower part of the stove adjacent the support to cool the supporting structures and simultaneously reduce the temperature of the gases as they move toward the stack outlet. This is illustrated, for example, in Figure 12 where the grids, designated 60, supported on the girders 61, carried on columns 62, are provided with pipes 63 extending therealong. These pipes have small openings therein for projecting streams of cooling fluid directly against

the grid bars 60. The grid bars being of small section and being directly under the checker brick column, are more susceptible to damage than any other part of the bottom. By introducing cooling fluid in this manner directly into the lower part of the stove, these grids are cooled and the volume of gases which flows on down around the girders 61 and columns 62 has its temperature somewhat reduced, depending of course upon the amount of fluid which is introduced through the pipes 63. If the fluid used for cooling the bottom structure be water, a considerable amount of heat will be absorbed as latent heat of vaporization. Also, sufficient water can be introduced so that some of it will flow down over the girders 61 and column 62 to cool them.

When the fluid is introduced in the manner described in connection with Figure 12, it is introduced only when the stove is on a heating cycle, and it is cut off as soon as the blowing cycle is started. The arrangement shown in Figure 7 is particularly desirable with the arrangement shown in Figure 12, when the cooling fluid is water, because any large accumulations of water may be drained off before the blowing cycle starts.

While we have illustrated and described certain embodiments of our invention, it will be understood that this is by way of illustration, and that various changes and modifications may be made within the contemplation of our invention and under the scope of the following claims. Also, while we have shown a stove in which the columns, girders and grids are entirely of metal, it will be understood that our invention is also applicable to stoves in which combinations of metal and masonry are used.

We claim:

1. A blast furnace stove having a checker-supporting structure therein comprised of columns, girders on the columns, grids on the girders, said columns, girders and grids being formed of hollow sections to provide water circulating ducts therethrough, means for supplying water to said sections, means for discharging water from said sections, all of the columns having a common discharge system, all of the girders having a common discharge system, and all of the grids having a common discharge system, the several discharge systems having means visible exteriorly of the stove for indicating an abnormal water condition in the system.

2. A blast furnace stove having a checker-supporting structure therein comprised of columns, girders on the columns, grids on the girders, said columns, girders and grids being formed of hollow sections to provide water circulating ducts therethrough, means for supplying water to said sections, means for discharging water from said sections, all of the columns having a common discharge system, all of the girders having a common discharge system, and all of the grids having a common discharge system, the several discharge systems having means visible exteriorly of the stove for indicating an abnormal water condition in the system, said means comprising a sight discharge device.

3. A blast furnace stove having a water-cooled metal bottom structure for supporting the checker work, a floor under the water-cooled bottom structure, means on the floor for collecting and draining away leakage water which may accumulate, and means for signalling the presence of accumulated leakage water at the floor of the stove to warn the operator of any leak in said water-cooled structure.

4. A blast furnace stove having a water-cooled bottom structure for supporting a superimposed column of checker brick, means for indicating a leakage in said water-cooled bottom structure, said means including a sump in the floor of the stove, a float in said sump, and electric signalling means controlled by said float.

5. A blast furnace stove having a metal structure for supporting a column of checker brick therein, said structure being formed of hollow metallic sections, and means for circulating cooling fluid through said sections, heat responsive means carried on some of said sections, and signal means externally of the stove controlled by said heat responsive means.

6. A blast furnace stove having a bottom for supporting the checker brick therein, said bottom comprising columns, girders supported on the columns, and a plurality of grid sections supported on the girders, the columns, girders and grid sections being formed to provide water-circulating ducts therealong, and a water supply system connected in parallel with all of the columns, a water supply system connected in parallel with all of the girders, and a third water supply system connected in parallel with all of the grid sections, and a discharge system connected in parallel with all of said columns and a discharge system connected in parallel with all of the girders, and a third water discharge system connected in parallel with all of the grid sections, said parallel systems enabling any failure to be readily detected and blocked off and subsequently rejoined.

7. A blast furnace stove comprising a vertically-extending housing having a column of checker brick therein with a chamber therebe-

neath through which hot gases flow after leaving the column of checker brick, a supporting structure for the checker brick located in said chamber and exposed to the hot gases which flow through the chamber comprising a horizontally-extending grid, means for cooling the grid, horizontally-extending girders supporting the grid, means for cooling the girders and vertically extending columns supporting the girders, and means for cooling the columns.
